US00D734149S

(12) **United States Design Patent**
McGrath, Jr. et al.

(10) **Patent No.:** **US D734,149 S**
(45) **Date of Patent:** **** Jul. 14, 2015**

(54) **CANISTER COVER**

(71) Applicants: **James W. McGrath, Jr.**, Daytona Beach, FL (US); **George M. Salg**, Enosburg Falls, VT (US)

(72) Inventors: **James W. McGrath, Jr.**, Daytona Beach, FL (US); **George M. Salg**, Enosburg Falls, VT (US)

(73) Assignee: **PBM Nutritionals, LLC**, Charlottesville, VA (US)

(**) Term: **14 Years**

(21) Appl. No.: **29/475,129**

(22) Filed: **Nov. 29, 2013**

(57)

CLAIM

The ornamental design for a canister cover, as shown and described.

DESCRIPTION

FIG. 1 is a perspective view of a canister cover.

FIG. 2 is a top view of the invention.

FIG. 3 is a front view of the invention.

FIG. 4 is a rear view of the invention.

FIG. 5 is a first side view of the invention; and,

FIG. 6 is a second side view of the invention.

In the drawings, the broken lines depict environmental subject matter that forms no part of the claim.
